UNITED STATES PATENT OFFICE.

REINHARD MOSMANN, OF ST. GALLEN, SWITZERLAND.

SOUND-REPRODUCING MACHINE.

Application filed March 1, 1922. Serial No. 540,235.

To all whom it may concern:

Be it known that I, REINHARD MOSMANN, a citizen of Switzerland, and residing at St. Gallen, Switzerland, have invented certain new and useful Improvements in Sound-Reproducing Machines, of which the following is a specification.

The present invention has reference to improvements in sound reproducing machines or phonographs of the enclosed or cabinet type, and it relates more specifically to improvements in means for modulating and amplifying the sound waves passing from the sound box through a sound conveyer, which includes the tone arm and horn, to the mouth of the latter, and the particular object of the invention is to provide an improved and novel type of sound controller and amplifier and to so mount the modulator and freely suspend this amplifier within the sound conveyer that the sound waves can readily be controlled as to their intensity, and that motor and other disturbing sounds and noises are not transmitted to the amplifier and then emitted from the horn, as is apt to be the case where the sounding boards of other types of amplifiers are in rigid contact with the walls of the machine casing or the sound conveyer.

The construction and arrangement of the parts of my invention is such that the tone quality is not in any way interfered with by foreign noises propagated in the main casing and the sound conveyer or horn, but that only the actual wanted sound waves emanating from the sound box are caused to impingly act upon the resonator parts and are thereby amplified and in this state issue from the resonance chamber.

My invention will best be understood when described in connection with the accompanying drawing, in which Fig. 1 is a vertical longitudinal section through a preferred embodiment of the invention, of which Fig. 2 shows a front view and Fig. 3 a plan. Fig. 4 is a vertical section through the modulator or damper, of which Fig. 4^a is a plan view. Fig. 5 is a front view of the amplifier proper, partly in section, and Figs. 6 and 7 respectively are longitudinal section and front elevation of a modification.

The tapering sound conveyer or horn 1, which is secured to the cabinet wall 4 by screws 5 passing through its rigid fastening plate 2 and an interposed sound-deadening

pad 3, may be of any conventional shape; as shown by way of example it is of gradually tapering conformation with square corners, but it may, obviously, also be of round, oval, or other cross-section. The attenuated upper end communicates with the tone arm support 6. In the wide forepart of the horn is suitably suspended from the top wall 7 the amplifier A. This latter, by way of example, comprises a top plate 10 and a bottom plate 10' interconnected at the corners by posts 9 and kept under stress in bow-shape by the interposed distance rod 11 with their concave surfaces in juxtaposition. The upper sound plate 10 carries a rib 8 by which the device is secured to the horn wall in any suitable manner, for instance by means of the screws 8', a sound-absorbing pad 8'' being interposed, as shown in Fig. 5.

Midway between these two sound plates 10 and 10' is suspended by the rod 11 a resonance board 12 provided with relatively large corner perforations 13 for the free passage of the posts 9. The plates together form a circumferentially open, subdivided resonance chamber and for their manufacture the best quality of resonance wood is chosen, such as is used for violins and like instruments. The middle plate 12 does not contact anywhere except in the centre at the point of suspension, and the plates 10 and 10' are concavely facingly flexed and stressed as described and shown. To the rear edge of the intermediate plate 12 there is secured at 14 the one end of a carrier arm 15, which is bent to follow the curvature of the sound duct and whose upper end supports the dished sound receiving and transmitting disc 16. This latter, which hereinafter will be referred to as sound transmitter, is only very slightly smaller in diameter than the horn cross-section at this point and is not in contact therewith in any way, and it thus directly receives by far the major part of the sound waves sent out by the needle-vibrated diaphragm and then transmits these sound vibrations over the member 15 to the amplifier proper.

In the drawing only one intermediate amplifier plate 12 is shown by way of example, but I want it to be understood that two or more such plates may be used to good advantage, in which case only one of them need be rigidly connected to the sound transmitter. Above the latter there is arranged

in the sound duct the modulator or damper 17, in the shape of a hinge flap of rigid material, fulcrumed in the horn wall and its fulcrum pin 18 extending through the wall, 5 as shown in Fig. 2. By manipulation of this pin 18 in any suitable manner, direct or by special connections not shown here, the sound passage through the horn may be controlled at will.

10 Figs. 6 and 7 show such a combined modulating and amplifying arrangement in connection with a prismatic sound conveyer, the sound transmitter 20 and the modulator 17' operating in a prismatic neck 22, which 15 arrangement allows of employing a relatively large resonance chamber with correspondingly enhanced sound volume over the conventional tapering horn constructions.

In use the sound waves, with the modulator flap open, will practically all directly impinge on the sound disc 16 (or 20 in Fig. 6) which will then transmit them to the amplifier A whose parts will be caused to vibrate and then pass on the amplified waves 25 without admixture of disturbing foreign sounds out of the mouth of the horn. On the modulator being closed more or less the sound waves will first impinge upon this obstruction and will then be propagated in 30 correspondingly damped intensity to the disc 16, so that by manipulating the modulator flap the tone strength can readily be controlled without interfering with the amplifier operation.

35 What I claim is:—

1. In a sound reproducing machine including a sound conveyer, an amplifier in said conveyer comprising a plurality of spacedly interconnected sound boards, and 40 a sound transmitter rigidly spacedly connected to one of said sound boards.

2. In a sound reproducing machine including a sound conveyer, an amplifier presenting a subdivided, circumferentially open resonance chamber, and a sound transmitter in rigid association with said amplifier, and said sound transmitter having a diameter to practically occlude said sound conveyer without, however, contacting therewith.

3. In a sound reproducing machine including a sound conveyer, an amplifier in said conveyer comprising three spacedly horizontally superposed, interconnected sound boards, and a sound transmitter in 55 rigid connection with, but spaced from, the middle one of said sound boards.

4. In a sound reproducing machine including a sound conveyer, an amplifier in said sound conveyer and comprising a top resonance plate, a bottom resonance plate, 60 and an intermediate resonance plate, all spacedly interconnected in substantially horizontal relative arrangement, a sound transmitter in said sound conveyer, and a rigid distance connection between said intermediate resonance plate and said sound transmitter. 65

5. In a sound reproducing machine including a sound conveyer, an amplifier, comprising top and bottom plates and intermediate means for subdividing the space between said plates, said intermediate means only centrally contacting with said plates, and said amplifier contacting with said sound conveyer only at a single point, and 70 a sound transmitter rigidly connected in spaced relation to said intermediate subdividing means. 75

6. In a sound reproducing machine including a sound conveyer, an amplifier comprising a top plate, a bottom plate, and an intermediate plate, all of resonant character, means cornerwise connecting said top and bottom plates, means for stressing said top and bottom plates in opposite sense and for 80 suspending said intermediate plate between them out of contact therewith except at a central point, and a sound transmitter in rigid connection with, but spaced from, said intermediate plate. 90

7. In a sound reproducing machine including a sound conveyer, in combination, an amplifier comprising a top resonator plate and a bottom resonator plate, means rigidly connecting said plates near their 95 circumference, and a central distance member for respectively outwardly flexing and stressing said two resonator plates, an unflexed resonator plate freely suspended intermediate said two flexed plates at a single 100 central point by said distance member and having perforations for the free passage of said rigid plate-connecting means, said amplifier contacting with said sound conveyer only at a single point of connection, a sound 105 transmitter in the contracted portion of said sound conveyer, and means for rigidly connecting said sound transmitter to said intermediate unflexed resonator plate.

In testimony whereof I affix my signature. 110

REINHARD MOSMANN.
